CLAIM

The ornamental design for a bicycle helmet as shown and described.

DESCRIPTION

FIG. 1 is a perspective view of a bicycle helmet embodying the design.

FIG. 2 is a front elevation view of the design shown in FIG. 1.

FIG. 3 is a rear elevation view of the design shown in FIG. 1.

FIG. 4 is a left elevation view of the design shown in FIG. 1.

FIG. 5 is a right elevation view of the design shown in FIG. 1.

FIG. 6 is a top plan view of the design shown in FIG. 1; and, FIG. 7 is a bottom plan view of the design shown in FIG. 1. The evenly broken lines in the drawings illustrate portions of the bicycle helmet that form no part of the claimed design. The dot-dash lines in FIGS. 2, 3, and 7 represent the bounds of the claim and form no part thereof.
